UNITED STATES PATENT OFFICE.

HENRY J. PLEAU, OF NASHUA, NEW HAMPSHIRE.

RIM-LOCK.

SPECIFICATION forming part of Letters Patent No. 541,947, dated July 2, 1895.

Application filed August 20, 1894. Serial No. 520,773. (No model.)

To all whom it may concern:

Be it known that I, HENRY J. PLEAU, of Nashua, in the county of Hillsborough and State of New Hampshire, have invented certain new and useful Improvements in Rim-
Locks, of which the following is a specification.

My invention relates to that class of locks known as rim locks, and its object is to provide a lock that cannot be unlocked from the outside by any other instrument or means than by using the key made expressly for it; also to so construct a lock that it will combine simplicity with greater strength than similar locks possess.

I will now describe the mechanism of my improved lock, together with the key that operates the same.

Similar letters refer to similar parts throughout the several views.

In the drawings, Figure 1 represents a plan of the inside of my improved lock with the cover removed. Fig. 2 is a plan of the front of lock, showing the knobs used to lock and unlock the same without using the key and from the outside of door. Fig. 3 is a cross-section through line $\alpha\alpha$ in Fig. 1. Fig. 4 represents the key and shows the manner of constructing the same.

30 a represents the casing of lock; b , the bolt which has a longitudinal movement in the same.

c is the escutcheon which receives the end of bolt when same is moved outward.

35 d is a stop which swings on the pivot c , and has the two members d' , and d^2 . The member d' swings in position behind the inward ends of bolt b , when same is in its outward position, and prevents it from being moved inward.

f is a socket pivoted in a hole in casing and has the knob g , attached to its outer end. When it is desired to move the bolt b , inward the socket f , is caused to perform a partial revolution by means of the knob g , or the key r , thereby swinging the member d' on its axis through the medium of the member d^2 , and the arm f' . Said movement causes the member d' , to be withdrawn from contact with the inner end of bolt b , permitting the same to have a free longitudinal movement.

e represents a flat spring which operates to

keep the stop d , in the position shown in full lines.

The dotted lines represent the stop d , withdrawn from behind the inner end of bolt b , and said bolt b , in its inward or unlocked position.

h represents a knob which operates in the slot i , and is attached to the bolt b .

j is a hole in the socket f , and is represented as being square, but I do not limit myself to that particular form, as I may wish to make it triangular, or of any desired regular or irregular shape.

l is a stop which limits the outward movement of the bolt b . Said stop l is also used to form a bearing for the plate which covers the working parts of the lock. Said plate is attached to the stop l by a countersunk headed screw.

m is a guard cast on the inside of casing in the path of the movement of key, the use of which will be explained in connection with the key.

The projections cast on the body of the lock and escutcheon designated by the letters n and n' , are used to secure the lock and escutcheon to the door and door jamb upon which the same are to be used.

The projections designated by the letter q , form a bearing for the plate which covers the working parts of the lock.

r represents the body or shank of key; s , the thumb pieces; t , the ward which operates the bolt b .

u is a square portion upon the end of a spindle which extends through a longitudinal hole in shank r , of the key, and v , is a thumb piece which is attached to the upper end of spindle u , by means of the pin w .

x' , x^2 , x^3 , x^4 are grooves in the ward t . x' is for no particular purpose. x^2 and x^3 correspond to projections on guard m , attached to casing a . x^4 is formed to receive the rim of socket f , as shown in Figs. 1 and 3.

The operation of my improved lock is as follows: In locking, the bolt can be thrown outward by means of the knob h , from the inside of the door, or by means of the key shown in Fig. 4 from the outside of the door. When the key is inserted in the key slot and turned it causes the ward t , of the key r , to operate in the recess o , in bolt b , thereby throwing

said bolt *b*, outward. In unlocking said lock from the inside, the operator first turns the knob *g*, to the right, thereby causing the trig *d'*, to swing from behind the end of bolt *b*, 5 when said bolt *b*, is moved inward by means of the knob *h*.

The operation of unlocking by means of the key is as follows: When key is inserted into the keyhole the square portion *u*, of the key 10 enters the socket *j*. Then by giving the thumb piece *v*, a partial turn it causes the projecting member *f*, to oscillate on its axis to position shown by the dotted lines, and at the same time causes the member *d*, to oscillate 15 through the medium of the arm *d'*, thereby causing the trig *d'*, to be withdrawn from behind the end of bolt *b*, and assume the position shown by the dotted lines. Then by turning the key by means of the thumb piece *s*, 20 the ward *t*, will operate in the recess *o*, and move the bolt inward.

The socket *t*, and member *u*, of the key may be made in different shapes without departing from the spirit of my invention.

25 I claim—

1. The combination in a rim lock, of the bolt *b*, having the knob *h*, attached to said

bolt *b*, and sliding in a groove in the body of said lock, with the member *f*, which has the socket *j*, arm *f'*, and the knob *g*, the member *d*, which has the arm *d'*, and the trig *d'*, and the spring *e*, all as and for the purpose set forth. 30

2. The combination in a rim lock, of the bolt *b*, having the knob *h*, attached to said 35 bolt *b*, and sliding in a groove in the body of said lock, the member *f*, which has the socket *j*, with a key having a straight shank, a hole extending longitudinally through said straight shank, a spindle fitting loosely in said hole in 40 shank, one end of said spindle being provided with an enlarged irregular shaped portion adapted to fit into hole *j*, the socket *f*, having the arm *f'*, and the member *d*, provided with the members *d'*, and *d''*, as and for the purpose set forth. 45

In testimony whereof I have signed my name to this specification, in the presence of two subscribing witnesses, this 4th day of June, A. D. 1894.

HENRY J. PLEAU.
